ABRADING APPARATUS

William A. Rosenberger, Hagerstown, Md., assignor to Pangborn Corporation, Hagerstown, Md., a corporation of Maryland

Application August 31, 1936, Serial No. 98,783

12 Claims. (Cl. 51—9)

This invention relates to abrading apparatus and more particularly to abrading machines of the character wherein the work is placed upon movable supports and passed through a blasting zone.

Machines of this general character have been heretofore proposed but they have not been altogether satisfactory because they have been of relatively high cost and have lacked the desired flexibility to handle a wide variety of sizes and shapes of work, have been somewhat difficult to load and unload and have been expensive to operate and maintain.

It is therefore a primary object of this invention to provide a novel abrading machine which will rapidly and efficiently clean articles of work of various sizes and shapes, which is low in initial and upkeep costs and which may be readily loaded and unloaded.

Another important object is to provide a novel abrading machine embodying a plurality of work supporting tables for conveying the work into a blast zone and having means for automatically causing the tables to rotate when they attain the blast zone, so as to subject all sides of the work to the abrasive stream.

A further object is to provide an abrading machine having means for conveying articles of work through a blast zone and subjecting them to the action of a blast stream thrown from at least one mechanical abrasive propelling device.

Another object is to provide an abrading machine having novel means for supporting and rotating the work while it is in the blast zone.

Another object is to provide novel abrasive recovering means, and novel table supporting and driving means for abrading machines of the character embodying movable means for carrying articles of work through a blast zone and the invention also aims to improve and refine certain other features of such machines.

Further objects of the invention will become apparent as the specification proceeds in connection with the annexed drawings.

In the drawings:

Figure 1 is a front view of the machine of the present invention and a part of the casing has been broken away in order to more clearly illustrate certain features of the construction;

Figure 2 is a top plan view of the machine illustrated in Figure 1;

Figure 3 is a side illustration of the machine shown in Figure 1, and illustrates the machine as it appears when viewed from the right hand side of that figure;

Figure 4 is a fragmental vertical sectional view of one of the work supporting tables and illustrates the bearing and pulley assembly;

Figure 5 is a vertical sectional view of the main table driving assembly of a machine shown in Figure 1;

Figure 6 is a diagrammatic view illustrating the manner in which the blast stream from the centrifugal wheel is directed upon the work tables;

Figure 7 is a fragmental top plan view of the belt tensioning means of the machine shown in Figure 1;

Figure 8 is a top plan view of the main table assembly with the work tables removed and the table plates disassembled to show the construction of the parts, and one of the abrasive scraper plates is shown assembled therewith;

Figure 9 is a side elevational view of one of the intermediate arms of the machine shown in Figure 1 and illustrates one of the abrasive scrapers in place thereon;

Figure 10 is a side elevational view of one of the partition arms of the machine shown in Figure 1;

Figure 11 is a top plan view of one of the main table plates of the machine shown in Figure 1;

Figure 12 is a vertical sectional view of a modified form of mechanism for intermittently advancing the rotatable structure; and

Figure 13 is a diagrammatic top plan view of one form of mechanism that may be applied to impart rocking movement to the actuating arm of Figure 12.

With continued reference to the drawings, wherein like reference characters have been employed to designate like parts throughout the several views thereof, the machine briefly described comprises a housing or cabinet H in which a structure S is mounted for rotation about a substantially vertical axis.

The rotatable structure supports a plurality of work supporting tables T which are movable into the path of the blast stream discharged from blast wheel C mounted on top of the cabinet. The spent abrasive is dropped into a trough B under the machine and is carried by a screw conveyor A into the boot of an elevator E. The elevated abrasive is discharged into a hopper and conveyed to an abrasive flow controlling mechanism F and is then fed back into the centrifugal wheel. Housing H preferably is provided with a cylindrical side wall 10, a flat bottom wall 11 and a flat top wall 12. As seen in Figure 3, the housing is provided with

a front extension 14 whose side walls have substantially the same radius and curvature as walls 10 of the housing so as to form a continuation thereof. Housing extension 14 brings the work supporting tables into a convenient position for loading and unloading as will clearly appear hereinafter.

Cabinet H is provided with a front wall 16 having a work entrance opening 17 provided therein. Opening 17 is preferably closed by means of a plurality of depending flexible baffle members 18 which are pushed aside by the work entering the machine, and yet which seal the entrance against abrasive leakage when they are closed. Housing H is provided with an exactly similar discharge opening (not shown) through which the work leaves the machine.

The floor of the machine is reenforced by girders 21 and secured to the floor over the central girders is a standard 22, which is secured down in any suitable manner as by means of bolts or the like. Standard 22 supports the rotatable structure. Mounted upon an anti-friction bearing 23 in a recess in the top of the standard is a relatively massive disc 24. The rotatable structure S comprises an upper cylinder or shell 26 and a similar lower cylinder or shell 27. Shells 26 and 27 are secured together by flanged joint 28 or the like and secured within shell 27, as by means of a welding operation or the like, is an annular plate 29 which is reinforced by a plurality of gusset plates 31. Plate 29 is detachably secured to disc 24 by means of nut and bolt assemblies 32.

The structure S is accordingly mounted for rotation about a substantially vertical axis in the machine and the lower edge of cylinder 27 is preferably provided with a comparatively massive ring 33 for reenforcing it against distortion under the weight of the apparatus. Secured to the outer surface of ring 33 by means of a binding strip 34 is a flexible sealing member 35 which may be made of fabric, rubber or any other desired sealing material. Seal 35 cooperates with the floor 11 to prevent abrasive from ricocheting and working up into the interior of cylinder 27. In order to prevent any abrasive that might get past the seal 35 from getting into the bearing there is preferably provided a downwardly extending baffle member 36 which is secured to the standard and extends in close proximity to the inner wall of cylinder 27.

The cylinders may be driven in any suitable manner but preferably the simple and compact structure shown in Figure 5 is employed. With continued reference to this figure, cylinder 26 extends upwardly adjacent the top of the housing and is welded or otherwise secured to a drum member 38 which is secured to a shaft 39 by means of a key 41. Shaft 39 is mounted for rotation in the apparatus in a bearing 42 which is supported in a channel 43 carried by the cabinet. Secured to the upper wall of the cabinet by means of a binding strip 44 is a sealing member 45 which frictionally cooperates with the outer surface of drum 38 to prevent stray abrasive from escaping to the atmosphere.

Secured to the upper end of shaft 39 by means of key 47 is a clutch member 48 having a plurality of driving lugs 49 which cooperate with the driving lugs 51 of a clutch member 52 which is secured to a shaft 53 by means of a key 54. Shaft 53 is mounted for rotation in a bearing 56 which is preferably integrally formed with a housing member 57, which is in turn supported

by a cylindrical casing structure 58 supported upon the top of the cabinet. Casing 58 is provided with inspection and service openings 59 and 61, and is secured to the top walls of the cabinet in any desired manner, as for instance by a plurality of brackets or the like. Bearing 56 is adapted to be lubricated by a pressure grease fitting 63 which is connected thereto by a pipe line 64. Clutch members 48 and 52 provide a predetermined degree of lost-motion between the parts and function as a universal joint so as to compensate for any mis-alignment of shafts 39 and 53.

Shaft 53 may be rotated in any desired manner to transmit power to shaft 39 and the rotatable structure, but preferably employed is a worm gear 66, secured to shaft 53 by means of key 67, and which meshes with a worm 68 carried by a shaft 69.

Secured to shaft 69 exteriorly of housing 57 is a sprocket wheel 71 (see Figures 1 and 2) which is driven by a sprocket chain 72 and a sprocket wheel 73, the latter being in turn driven by the unitary speed reducer 74 of a motor 75 supported on the top of the housing.

From the structure so far developed, it is apparent that rotatable structure S is driven by motor 75, speed reducer 74, worm gear 66, clutch members 52 and 48, and shafts 39 and 53. The load of the assembly is taken by thrust bearing 23, whereas the upper part of the cylinders is maintained in vertical alignment by means of bearing 42.

Secured to lower cylinder 27, as by means of a welding operation or the like, are a plurality of outwardly extending fins or vanes 77 to which are secured all of the rotatable parts of the mechanism. Secured to certain of these vanes are preferably eight table supporting arms 78, which are each provided with a web 79 for reenforcing them against downward deflection under the load of the work.

Supported on the outer end of each arm 78 (Figure 4) is a shaft 79, and mounted on each shaft 79 is a pulley 81 by means of a pair of anti-friction bearings 82 and 83. Bearing 82 is retained in a recess in pulley 81 by means of a pair of plates 84 and 85, and a plurality of cap screws 86. A sealing member 87 is clamped between plates 84 and 85 and frictionally cooperates with the outer surface of shaft 79 to prevent abrasive from working its way into the bearing.

Bearing 83 is retained in a recess in the upper side of the pulley by means of a cap member 89, which is secured to the pulley by means of a plurality of cap screws 91. Bearing 83 is maintained in place on shaft 79 by means of a washer 92 and a cap screw 93, the latter being threaded into the upper end of the shaft. Integrally secured to cap member 89, preferably by a welding or like operation is a shaft 94 having a tapered upper end 95 and a cross pin 96. Each table is provided with a hub 97, fitting over tapered surface 95 of shaft 94, and having a pair of bifurcations 98 which embrace cross pin 96 for establishing a positive driving connection between shaft 94 and the tables. The tables may accordingly be freely lifted out of the apparatus for service and replacement. Each table is provided with a plurality of arms 101 terminating in a circular rim 102. Seated upon the arms and rim is a perforated plate 103 which is in turn surmounted by a perforated, preferably rubber pad 104, upon which the work is adapted to be supported. Pad 104 being resilient, absorbs the energy of the

abrasive that strikes it and accordingly has a long life.

Preferably integrally formed on each arm 108 is an ear 106 (see Figure 8) to which a strut 107 is secured. The free ends of each strut are provided with an angle portion 108, and they are rigidly secured to the intermediate portions of an arm 109, which will be hereinafter referred to as a partition arm, and it is more clearly illustrated in Figure 10 of the drawings, there being one partition arm for each pair of table supporting arms. The outer end of the partition arm is provided with a recess 109a, to allow clearance for the table driving belt of the apparatus, which will be hereinafter described. Bolted or secured in any other suitable manner to the lower edge of each partition arm is a resilient, preferably rubber, sealing member 109b.

Supported intermediate each pair of table arms is an intermediate arm 110, which is also secured to fins 11 of lower cylinder 27. The free ends of the partition and intermediate arms support a cylindrical band or rim 111, which is secured thereto in any suitable manner, and as seen in Figure 2, band 111 terminates closely adjacent to, but is spaced from the side walls 10 of the cabinet. Supported on the upper surface of arms 109, 110 and rim 111, are a plurality of perforated plates 112, and as seen in Figure 11, they are provided with semi-circular openings 113 to provide a clearance about the hubs of tables. Also secured to plates 112 are a plurality of strips 112a and 112b, which overlap the neighboring plate and seal the joint.

The rotatable structure accordingly provides what is in effect a large table defined by the upper surfaces of the plates 112, and upon which are mounted a plurality of small tables T, which are bodily conveyed by the large table and are mounted for independent rotation about their axis. The abrasive which falls through the perforations in plates 112 drop onto the upper surface of floor 11 where it is swept or propelled around to abrasive conveying trough B by means of a scraper assembly that will now be described.

Referring to Figures 8 and 9, a scraper assembly is preferably mounted on each intermediate arm 110 (which are four in number) and each scraper comprises a member providing horizontal portions 114 and 115 which, as seen in Figure 8, are inclined with respect to a radius. Portions 114 and 115 are provided with brackets 116 and 117, respectively, and each bracket is provided with an elongated opening 118. Bolt and nut assemblies 119 cooperate with the brackets and with openings in the intermediate arm to support the scraper upon the rotatable structure.

The scrapers are so mounted on arms 110 as to have a predetermined clearance with respect to floor 11. The proper adjustment may be readily effected by loosening bolt and nut assemblies 119, raising or lowering the scrapers and then tightening the parts to hold them in locked position. As previously pointed out, the abrasive drops onto floor 11, and by reason of their inclination portion 114 pushes the accumulated abrasive outwardly and portion 115 pushes the abrasive inwardly, thereby forming a concentrated pile of abrasive in front of each scraper. As each scraper attains a predetermined position in the rotation of structure S, its accumulated pile of abrasive drops into trough B. During operation of the machine, partitions 109 prevent the abrasive from freely rebounding from one part of the device to another, and efficiently baffle the abra-

sive against rebounding out of the machine. Also, sealing strips 109b terminate close to the floor of the machine and provide a joint that is substantially abrasive-tight.

5 Although any suitable abrading apparatus may be employed for discharging a stream or streams of abrasive downwardly upon the work supported upon the tables, I preferably employ a centrifugally operable wheel assembly, mounted within 10 an open bottomed cabinet 125 over an opening in the top wall of the main housing. As more clearly illustrated in Figure 6, the apparatus comprises a wheel or rotor 126 having a plurality of substantially radial blades 127 secured there- 15 to and which terminate short of the axis to provide an abrasive admitting space in which an abrasive feeding device 128 is located. Chamber 128 mounted with an outlet 129 for feeding the abrasive over the inner ends of the blades. In 20 order to prevent the abrasive from choking, to also impart an initial velocity thereto, an impeller 131 is secured to rotor 126 and extends within chamber 128. Rotor 126 is driven at high speed by means of a motor 133 mounted on the top of the cabinet and which is connected to rotor 126 by means of a pulley and belt assembly 134.

25 The abrasive is fed to the centrifugal wheel by means of a feed spout 135 leading from the abrasive control mechanism. As the centrifugal abrading machine disclosed forms no part of the present invention, no claim is made thereto and it will therefore not be further described. Also, the centrifugal wheel may be mounted in the machine with its axis disposed at a different angle, than that shown. For instance, the wheel may be arranged to discharge the fan-like stream transversely to the path of movement of the work if desired.

30 40 As seen in Figure 6, the abrasive discharged from the wheel assumes a fan-like configuration and is discharged downwardly from the work supported upon tables T, while the tables move forwardly bodily in the direction indicated in 45 that figure, and while they simultaneously rotate about their axis in the direction indicated. Tables T are caused to rotate in this manner by the structure that will now be described.

45 50 Mounted on the top of the cabinet is a motor 131 having a unitary speed reducer assembly 138 terminating in a power shaft 139 carrying a sprocket 141. A sprocket chain 142 meshes with sprocket 141 and drives a sprocket 143 carried by a shaft 144. Shaft 144 extends downwardly outside of housing H and is journaled in a bearing 145. Mounted on shaft 144 adjacent bearing 145 is a pulley 146. Journaled on the opposite side of the cabinet is a pulley 147. Mounted on the back of the cabinet is an idler pulley assembly 60 more clearly shown in Figure 7 and which comprises a standard 149 upon which a pair of bell crank levers 151 are pivoted by means of a shaft 152. Bell crank levers 151 support an idler pulley 153 and they are urged toward belt-tightening position by means of a tension spring 154. Spring 154 is anchored to a bolt member 155 which passes through a bracket 156 supported on the cabinet. Bolt member 155 may be adjusted to increase or decrease the tension of spring 154 by means of a pair of nuts 157 and 158.

65 70 As seen in Figures 2, 3 and 7, a belt 159 passes between pulleys 146 and 147 and one reach thereof passes around tensioning pulley 153. As seen in Figure 2, one reach of belt 159 passes through

suitable openings in the housing side wall and cooperates with the pulleys 81 of tables T.

It is accordingly apparent that as the main structure rotates in the direction indicated in Figure 2, the small tables will be successively passed through the blast zone. As they approach the blast zone, pulleys 81 will be successively engaged with belt 158 and rotated in the direction indicated in Figure 2. If desired, however, the direction of belt 158 may be reversed so as to cause the tables to rotate in the opposite direction. In view of the fact that the tables rotate continuously while they are in the blasting zone, all of the upper surfaces of the work are subjected to blasting streams at different angles and are subjected to the most intense part of the blast stream. When the tables pass out of the blast zone, they become disengaged from belt 158 and come to rest, so that by the time they reach the front of the cabinet, or the loading and unloading station, they are stationary and the work may be readily removed and replaced by new work. If desired, however, if the work requires a further cleaning action, the work may be left upon the tables to again pass through the blast zone. Although the speeds of the various parts will be varied to meet the desired conditions under which it is desired to operate the machine, it has been found that suitable speeds for general abrading are two-thirds R. P. M. for structure S and 32 R. P. M. for the work supporting tables.

Although I have illustrated a machine wherein the main supporting structure is rotated at a predetermined speed, so as to constantly and progressively bring the work through the blasting zone, if desired, a mechanism may be employed for intermittently advancing the table so as to cause each table to be brought into, and caused to dwell for a predetermined time in the blast zone. In Figures 12 and 13 I have illustrated an advancing mechanism of this character.

With continued reference to Figures 12 and 13, shaft 39, which is connected to drum 38, is journaled in bearing 42 as in the first form of the invention. Secured to the upper end of shaft 39, by means of a pair of cap screws 165 and a key 166, is a sleeve or jaw clutch member 167 having inclined teeth 168. Surrounding the upper end of shaft 39 and resting on a shoulder 169 provided on jaw clutch member 167 is a hollow hub 171 of a lever 172. Lever 172 is restrained against upward displacement from shaft 39 by means of a plate 173, which engages the upper surface of hub 171 and is secured to shaft 39 by means of a pair of cap screws 174. Plate 173 is provided with an annular shoulder 175 which provides a bearing for hub 171.

Surrounding shaft 39 and mounted for vertical reciprocation in hub 171, is a jaw clutch member 177 having clutch teeth 178 at its lower end which cooperate with the clutch teeth 168 of jaw clutch member 167. Secured to jaw clutch member 177 by means of screws 179 are a pair of keys 181 which slide in guideways 182 provided in hub 171. Member 177 may accordingly reciprocate vertically within hub 171 but is restrained against rotation with respect thereto.

Jaw clutch member 177 is urged downwardly into cooperation with the teeth of jaw clutch member 167 by means of a compression spring 183, which reacts against the bottom of plate 173. A pair of oil cups 184 are preferably provided in plate 173 and supply lubricant to an annular 75

wick member 185, which in turn feeds oil to the guideways 182, and the other moving parts.

It is accordingly apparent that as four clutch teeth are employed on the jaw clutch members, 5 rocking lever 172 through an arc of approximately 90° in one direction causes jaw clutch member 177 to ride upwardly on teeth 168 of jaw clutch member 167 against the action of spring 183, and when it has reached the end of its idle stroke 10 the teeth will snap into engagement. Upon rocking the lever 90° in the other direction, shaft 39 and structure S will rock through an angle of approximately 90° by reason of the driving connection established by keys 181 and jaw clutch members 167 and 177.

Although lever 172 may be reciprocated in any suitable manner by any suitable means, in Figure 13 there is diagrammatically illustrated one form of mechanism that may be used. With continued reference to this figure, lever 172 is connected to an actuating lever 191 by means of a link 192. Lever 191 is pivoted for oscillation about an axis 193. Lever 191 is of channel formation and cooperating with the flanges thereof is a roller 194 carried by a crank pin 195. The 20 crank arm carrying pin 195 (not shown) is mounted for rotation about an axis 196 and is driven by any suitable prime mover at any desired suitable speed.

With crank pin 195 rotating in the direction illustrated in Figure 13, it is apparent that roller 194, operating between the channels of lever 191, will rock lever 172 counter-clockwise and advance the table 90° and will then rock lever 172 clockwise during a retracting or idling stroke to bring the jaw clutch members into locking relationship preparatory to another advancing stroke. In view of the fact that when the parts are undergoing the advancing stroke, roller 194 is disposed to the right of axis 196 and therefore possesses a comparatively short lever arm with respect to axis 193 of the lever, levers 191 and 172 will move comparatively rapidly and thereby relatively rapidly advance the table. On the other hand, when roller 194 is moving through an arc disposed at the left of pivot 196. Lever 191 will move comparatively slowly to bring the parts into retracted condition. Therefore, the mechanism even though driven at constant speed, will advance the work comparatively rapidly and then permit it to dwell in the blasting zone for a comparatively long period during the retracting stroke of the mechanism.

Although the jaw clutch members have but four teeth, and eight tables are employed in the machine, which makes it necessary to place two tables in the blast zone during each advance of the main table, if desired, the number of teeth on the jaw clutch members may be increased to eight so that the tables may be brought into the blast zone one by one.

Although the inclination of the teeth in the device shown in Figures 12 and 13 is such as to rotate the table in the opposite direction from that shown in Figure 1, it is to be understood that the machine functions in the same general manner and that the direction of the jaw clutch teeth may be reversed to impart rotation to the table which is similar in direction to that of the machine first described.

Although there has been shown a rotatable structure which bodily conveys the auxiliary tables in definite circular paths, it is to be understood that if desired the conveying means may take the form of a mechanism for causing the

tables to travel in rectilinear paths joined by curvilinear paths without departing from the spirit of the invention.

Reviewing the operation of the apparatus, the various motors, are started and a worker is stationed at the front of the machine and places the work to be cleaned upon tables T as they successively arrive at the loading and unloading station. The control mechanism F is then actuated to discharge the proper grade and quantity of abrasive into feed conduit 135, whence it flows to the centrifugal wheel and is discharged downwardly as previously described. Rotatable structure S, whether it is driven at constant speed or is intermittently advanced, conveys the work into the blast zone, efficiently subjects it to the action of the blast stream and then conveys it to the unloading station where it is removed and replaced by new work.

The abrasive which rebounds from the work and other parts of the apparatus is prevented from escaping by the walls of the housing and also cylinders 26 and 27 and drops upon the main table surface, where it passes through the perforations thereof and drops upon the floor. The scraper assembly then carries the abrasive to trough B where it is conveyed to the elevator by screw conveyor A. The abrasive is lifted into an abrasive washing and separating device (not shown) where any casting fragments, nails and other extraneous material is removed and the fins and dust are also separated out. In order to prevent the surface of plates 112 between the tables from being excessively abraded I preferably provide a plurality of rubber pads 198 between the tables and which may if desired be perforated to facilitate draining the abrasive to the floor of the machine.

In order to prevent dust and fine abrasive particles from finding their way into the atmosphere the cabinet is preferably provided with a pair of exhaust conduits V which are connected to a suction fan and dust collector assembly (not shown). Suction pipes V place the interior of the cabinet under a slightly sub-atmospheric pressure, thereby preventing dust leakage into the atmosphere, even when flaps 18 are pushed aside by the work in entering and leaving the cabinet.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. In an abrading apparatus, a housing constituting a blasting chamber, a structure mounted for rotation within said housing and adapted to support and present articles of work to the action of a blasting apparatus, said structure embodying an upright cylindrical member terminating in a shaft projecting above the top of said housing, means for journaling said shaft upon said housing, a second shaft journalled upon said housing in alignment with said first shaft, a universal joint coupling said shafts for synchronous rotation, and means for driving said second shaft.

2. The abrading apparatus described in claim 1, wherein said first shaft is journalled in a casing mounted on said housing and said second shaft

is journalled in a worm gear housing mounted on the top of said casing and carries a worm gear meshing with a worm mounted for rotation in said worm gear housing.

5. In an abrading apparatus, a structure mounted for rotation about a substantially vertical axis, a plurality of horizontally disposed arms radiating from said structure and rotatably carrying work supports near their free ends, a plurality of elements radiating from said structure intermediate said arms, said elements being longer than said arms and carrying a generally circular rim at their outer ends, a plurality of struts interconnecting the free ends of said arms and the intermediate portions of certain of said elements, and a plurality of table-forming plates carried by said elements and said rim, said plates being disposed at a level intermediate said work supports and the free ends of said arms.

20 4. The abrading apparatus described in claim 3, wherein said structure is disposed within a cylindrical housing having a vertical cylindrical wall surrounding but spaced from the periphery of said circular rim for preventing abrasive from leaking therebetween, said wall terminating substantially flush with said table-forming plates throughout a substantial arc for providing a low level loading and unloading station.

30 5. In an abrading apparatus, in sub-combination, a work supporting table-assembly comprising a substantially vertical shaft for rotatably supporting said table, a pulley journalled upon said shaft by means of at least one anti-friction bearing, a cap member detachably secured to the upper side of said pulley and operable to maintain said bearing in place, said cap member also being provided with an upwardly extending portion, and a work supporting table supported upon said upwardly extending portion of said cap member for synchronous rotation therewith.

35 6. In an abrading apparatus, a structure mounted for rotation about a substantially vertical axis in a housing, said housing having a floor, sides and a roof, a plurality of arms radiating from said structure and rotatably carrying work supports near their outer ends, means for directing at least one blast stream downwardly upon said work supports, a plurality of elements radiating from said structure intermediate said arms, said elements being longer than said arms and carrying a generally circular rim at their outer ends, a plurality of table-forming plates carried by said elements and said rim, said plates being disposed at a level intermediate said work supports and the outer ends of said arms, said elements also comprising vertical partitions of considerable area extending downwardly into close proximity to the floor of said housing for preventing abrasive from rebounding out of the apparatus.

60 7. The abrading apparatus set forth in claim 5, wherein said anti-friction bearing comprises an outer race piloted in a recess in said pulley and an inner race encircling said shaft, said cap member having a flange piloted in said recess and operable to maintain said outer race in position therein, and a plurality of screws passing through apertures in said cap member and maintaining the same in clamping engagement with said pulley.

65 8. In an abrading apparatus, a work supporting structure providing a shaft portion having a plurality of axially directed ratchet teeth, said shaft portion having a reduced diameter shaft projecting beyond said teeth, a hollow hub ele-

ment journaled for rocking movement about said shaft and shaft portion and having means for imparting rocking movement thereto, said hub element being spaced from said shaft so as to provide an annular space therebetween, a pawl disposed in said annular space and having means for keying it to said hub element and yet permitting axial movement thereof, said pawl having a plurality of axially directed teeth cooperating with the ratchet teeth of said shaft portion, and means for resiliently urging said pawl toward said shaft portion.

9. The abrading apparatus described in claim 8, wherein said hub element is journaled at one end directly upon said shaft portion and at its other end is journaled upon a plate detachably secured to said shaft.

10. In an abrading apparatus, a structure mounted for rotation about a substantially vertical axis, a plurality of horizontally disposed arms radiating from said structure, rotatable work supports mounted on said arms, a plurality of elements radiating from said structure intermediate said arms, a generally circular rim mounted on the outer ends of said elements, a plurality of struts interconnecting said arms and the intermediate portions of said elements, and a plurality of table-forming plates mounted on said elements and said rim, said plates being dis-

posed at a level intermediate said work supports and said arms.

11. The abrading apparatus described in claim 10 wherein said structure is disposed within a 5 cylindrical housing having a vertical cylindrical wall surrounding but spaced from the periphery of said circular rim for preventing abrasive from leaking therebetween, said wall terminating substantially flush with said table-forming plates 10 throughout a substantial arc for providing a low level loading and unloading station.

12. In an abrading apparatus, a housing, means on said housing to project a stream of abrasive therein at blasting velocity to define a 15 blasting zone, and means to convey work through said blasting zone comprising a substantially vertical member in said housing, a substantially vertical cylindrical shell of a materially greater diameter than said member encircling and spaced 20 from said member, a bearing between an upper part of said cylindrical shell and said vertical member to rotateably mount said shell, a plurality of radiating arms supported by and extending radially from a section of said shell adjacent the 25 bottom thereof, work supporting means on said arms, and means to effect rotation of said shell to move said work supporting means into and out of said blasting zone.
